UNITED STATES PATENT OFFICE.

EVERETT H. BARNEY, OF SPRINGFIELD, MASSACHUSETTS.

IMPLEMENT FOR ATTACHING WASHERS ON ROLLER-SKATES.

SPECIFICATION forming part of Letters Patent No. 319,775, dated June 9, 1885

Application filed January 12, 1885. (No model.)

To all whom it may concern:

Be it known that I, EVERETT H. BARNEY, a citizen of the United States, residing at Springfield, in the county of Hampden and State of Massachusetts, have invented new and useful Improvements in Implements for Manipulating the Wheel-Fastenings of Roller-Skates, of which the following is a specification.

This invention relates to improved implements for securing wheel-fastenings to and removing them from roller-skate axles, the object being to provide convenient and effective means for operating devices for securing wheels upon axles, such as are described and shown 15 in my patent dated October 3, 1882.

In the drawings forming part of this specification, Figures 1 and 2 are side elevations of an implement embodying my invention; and Figs. 3 and 4 are perspective views of parts of 20 the same, showing the handles partly broken off. Fig. 5 is a section on the line xx , Fig. 3.

In the drawings, B is the implement embodying generally the form of pliers, but having its jaws aa adapted to the purposes of this 25 invention by forming in one side thereof curved recesses ee , which, as shown in Fig. 5, are slightly cut under at their base, and by having the studs cc placed in the sides of the jaws a opposite to those in which said recesses 30 are. The studs c project beyond the sides of the jaws, and the sides of the studs next to the opening between the jaws are made somewhat sharp, or of a V shape, as shown. The handles of the tool are indicated by o , and are 35 pivoted together at z .

The wheel-fastening above referred to, as shown in said patent, consists of an axle having an annular groove around it near its end, and a split washer is provided capable of fitting into said groove, and of having its separated edges forced together, and its inner cir-

cular border at the same time forced into the said groove in the axle, making a rigid circular shoulder outside of the wheel on the axle to hold the wheel on. In the drawings, b represents sections of the said axle near the end thereof, and e said split washer. In Fig. 3 are shown the positions of the axle, the washer, and the tool in the act of forcing the washer around the axle. The washer e is placed between the jaws a , with its edges in the recesses e , its split side outward, and then, being placed on the axle at its grooved point, the tool is shut, forcing the washer to the position shown in Fig. 3. The aforesaid undercut form 55 of the base of recesses e causes the washer to rest more firmly therein when the latter is sprung together on the axle.

To remove the washer from the axle, the tool is placed on the washer so that the V-shaped edge of one of the studs c is in the slight opening at the outer end of the split in the washer and the other stud resting against the opposite edge of the washer, and the jaws a , being then forced together, the washer is sprung 60 open, (as partly shown in Fig. 4,) and may be easily removed from the axle, so that the wheel can be taken off, the stud c having been forced between the adjoining ends of the washer, and thereby spreading them sufficiently. 70

What I claim as my invention is—

The implement B, having in its jaws, at one side thereof, the curved recesses ee , and on the opposite side of said jaws the studs cc , projecting beyond the side of the latter, each of 75 said studs having a V-shaped edge on the side thereof next to the opening between the jaws, substantially as set forth.

EVERETT H. BARNEY.
